SUSAN SERVER

William D. Warren, New York, N. Y.

Application April 8, 1957, Serial No. 45,628

Term of patent 14 years

(Cl. D44—10)

FIG. 1

FIG. 2

FIG. 3

FIG.4

FIG.5

FIG.6

FIG.7

FIG.8

FIG.9

Fig. 1 is a top plan view of a susan server embodying my new design;

Fig. 2 is a front view thereof;

Fig. 3 is a front perspective view thereof;

Figs. 4, 5, and 6 are respectively top plan, front, and front perspective views of an alternative way of arranging the trays of the susan server; and

Figs. 7, 8, and 9 are respectively top plan, front, and front perspective views of a still different alternative way of arranging the trays of the susan server.

I claim:

The ornamental design for a susan server, as shown.
